(57) **CLAIM**

The ornamental design for a motorcycle fairing, as shown and described.

DESCRIPTION

FIG. 1 is a perspective view taken from a front, left side of a motorcycle fairing according to our design;

FIG. 2 is a perspective view taken from a rear, left side thereof;

FIG. 3 is a perspective view taken from a front, right side thereof;

FIG. 4 is a perspective view taken from a rear, right side thereof;

FIG. 5 is a top plan view thereof;

FIG. 6 is a front elevation view thereof;

FIG. 7 is a left side elevation view thereof;

FIG. 8 is a rear elevation view thereof;

FIG. 9 is a right side elevation view thereof;

FIG. 10 is a bottom plan view thereof; and,

FIG. 11 is a perspective view taken from a front, left side thereof shown on a three-wheeled vehicle shown in dashed lines.

Throughout the Figures, where shown: (i) the unshaded surfaces form no part of the claimed design; and (ii) the dotted/dashed lines illustrate unclaimed boundaries of surfaces claimed as part of the design.
